Primary Examiner — Daniel Bui(74) *Attorney, Agent, or Firm* — Stephen R. Yoder, Esq.(57) **CLAIM**

The ornamental design for a sealing boot, as shown and described.

DESCRIPTION

FIG. 1 is a top, front perspective view of a sealing boot showing our new design;

FIG. 2 is a top, back perspective view thereof;

FIG. 3 is a top plan view thereof, the bottom plan view being a mirror image thereto;

FIG. 4 is a left side elevation view thereof, the right side elevation view being a mirror image thereto;

FIG. 5 is a front elevation view thereof; and,

FIG. 6 is a back elevation view thereof.

The broken line portion of the figure drawings is included to show unclaimed subject matter only and forms no part of the claimed design.
